LASTING MACHINE

Bernhardt Jorgensen, Marblehead, Mass., assignor to United Shoe Machinery Corporation, Flemington, N. J., a corporation of New Jersey

Application February 19, 1947, Serial No. 729,568

33 Claims. (Cl. 12—10.5)

1

This invention relates to lasting machines and has particularly in view the provision of certain improvements in a toe-lasting machine constructed generally as disclosed in United States Letters Patent No. 2,324,509, granted on July 20, 1943, on an application of mine, although preferably modified in some respects as disclosed in other Letters Patent granted on applications of mine, especially those hereinafter mentioned. The invention is accordingly herein shown as applied to such a machine, but it is to be understood that it is not limited to the illustrative embodiment.

The above-mentioned machine includes, among its lasting instrumentalities, a plurality of grippers which grip the margin of the toe-end portion of the upper and apply a pull to the upper in the toe-lasting operation, these grippers comprising an end gripper which grips the margin of the upper about the end of the toe and side grippers which grip it at the opposite sides of the toe. The end gripper is movable lengthwise of the last and the side grippers widthwise of the last to pull the upper, the grippers also receiving upper-pulling movements heightwise of the last. The several grippers are so arranged that in gripping the upper their jaws are relatively movable generally heightwise of the last, and it is therefore necessary that the margin of the upper be positioned between the jaws in outspread relation to the edge of the shoe bottom. When a shoe is presented to the machine it has been subjected to the usual pulling-over operation and customarily also it has been lasted along the sides of the forepart beyond the toe portion. Accordingly the portions of the margin of the upper which are to be engaged by the side grippers are near portions thereof which have already been secured over the bottom face of the insole. To permit the margin at the sides of the toe to be readily outspread, so that it will lie between the jaws of the side grippers when the shoe is presented to the machine, the above-mentioned Letters Patent discloses the practice of slitting the side edges of the upper in locations near where its toe-end portion terminates. It may not be desired, however, to follow this practice, and in that case it is necessary for the operator to hold the margin of the upper outspread with his fingers in locations adjacent to the portions already secured over the insole until the grippers have closed on the upper.

One object of this invention is to relieve the operator of the necessity of controlling the margin of the upper as above described, thus saving time and increasing the output of the machine.

2

For this purpose the machine herein shown is provided with novel means for properly positioning the margin of the upper between the jaws of the side grippers. More particularly, the construction shown comprises what may be termed upper-spreading fingers arranged to engage the margin of the upper in locations between the side grippers and the portions of the margin already secured to the insole, the fingers having components of movement heightwise and widthwise of the last to spread or deflect the margin outwardly between the gripper jaws. The fingers are thus operated by fluid-pressure means coincidentally with the closing of the jaws by other such means, their closing, however, being retarded to insure that the upper will be properly positioned before it is gripped.

Another object of the invention is to provide means for properly positioning the shoe as a whole without the necessity for any great care on the operator's part in presenting it to the machine. For this purpose the construction shown comprises shoe-positioning members arranged to engage the opposite sides of the forepart of the shoe and to be forced apart equal distances by the shoe as it is presented between them to position the shoe laterally, its position lengthwise being further determined by engagement of its toe-end face with one of the jaws of the end gripper. Through the shoe-positioning members at the sides of the shoe also the above-mentioned upper-spreading fingers are properly positioned widthwise of the shoe relatively to the margin of the upper, both the positioning members and the fingers being supported by arms which are connected together for equal swinging movements in response to pressure of the shoe on the members. Additional fluid-pressure means is provided for swinging the arms farther apart after the grippers have been closed and after the shoe has been clamped in the position determined, the shoe-positioning members and the fingers thus being withdrawn from the shoe and carried to positions where they will not interfere with lasting instrumentalities which thereafter operate on the shoe.

The above and other features of the invention, including various novel details of construction and combinations of parts, will now be more particularly described with reference to the accompanying drawings and thereafter pointed out in the claims.

In the drawings,

Fig. 1 is a view in front elevation of the upper portion of the machine to which the invention is herein shown as applied;

Fig. 2 is a view mainly in front elevation of portions of the structure located, for the most part, immediately at the rear of the front frame plate of the machine and in which features of the invention are embodied, the parts being shown in the positions which they occupy when a shoe is first presented to the machine;

Fig. 3 is a section on the line III—III of Fig. 1 on an enlarged scale;

Fig. 4 is a section on the line IV—IV of Fig. 1, also on an enlarged scale;

Fig. 5 is mainly a plan view showing parts as they appear in relation to the shoe at the same time as in Fig. 2;

Fig. 6 is a view similar to Fig. 5 of a portion of the structure, but with the parts as they appear when the margin of the upper has been positioned by the upper-spreading fingers;

Fig. 7 is a view partly in front elevation and partly in section, showing one of the upper-spreading fingers in the same position as in Fig. 6 before the grippers are fully closed;

Fig. 8 is a view similar to Fig. 7, showing the parts as they appear just after the upper-spreading fingers and the shoe-positioning members have been withdrawn from the shoe;

Fig. 9 is a vertical sectional view lengthwise of the shoe illustrating the relation of the shoe to the end gripper when the shoe is presented to the machine;

Fig. 10 is a vertical sectional view further illustrating the relation of one of the side grippers to the upper when the shoe is presented;

Fig. 11 is a vertical sectional view showing a valve which controls the closing of the grippers; and

Fig. 12 is a diagrammatic view of the fluid-pressure system in its relation to operating parts provided by the present invention.

In view of the disclosures in the previously mentioned Letters Patent and in others herein-after mentioned, only as much of the machine is herein shown in detail as it is necessary to refer to for an understanding of the invention, and such parts as are common to the prior disclosures will be only briefly described. The machine is a fluid-operated toe-lasting machine having a toe-end gripper 2 which grips the margin of the upper outspread about the end of the toe and side grippers 4 which grip it respectively at the opposite sides of the toe, the end gripper being moved lengthwise of the last and the side grippers widthwise of the last to apply a pull to the upper in those directions and the several grippers also being moved heightwise of the last further to pull the upper by upward swinging movement of a support 5 (Fig. 1) on which they are mounted. The end gripper (Fig. 9) has a lower jaw 6 toward which a cooperating jaw 8 is moved heightwise of the last to grip the outspread margin of the upper, and similarly each side gripper has a lower jaw 10 (Figs. 2 and 10) toward which a cooperating jaw 12 is moved heightwise of the last in the upper-gripping operation. Preferably the jaws have smooth upper-gripping faces, as shown, and in the upper-pulling operation slip to some extent on the upper in accordance with the disclosure of Letters Patent No. 2,377,887, granted on June 12, 1945, on an application of mine.

Also included in the lasting instrumentalities is a toe former 14 formed to embrace the upper about the toe end of the last and movable upwardly to wipe the upper heightwise of the last while the grippers are holding it under tension.

While the upper is thereafter held by the toe former its margin is operated upon by upper-trimming means to remove therefrom all but the outer layer of the upper materials, the grippers releasing the upper in the course of the upper-trimming operation. The upper-trimming means is not herein shown in detail, but includes an end knife 16 (Fig. 1) movable lengthwise of the shoe and side knives 18 movable widthwise of the shoe from positions over the bottom of the toe end of the shoe. The machine preferably includes means to cause the toe former 14 to release the upper after the upper-trimming operation and to repeat its upward wipe thereon and also to cause the grippers again to grip and pull the upper while acting only on the outer layer of the upper materials, as disclosed in the last-mentioned Letters Patent and in greater detail in Letters Patent No. 2,337,558, granted on December 28, 1943, on an application of mine. Thereafter cement is applied to the toe end of the shoe by means not herein shown and wipers 20, which are moved upwardly with the toe former, are operated to wipe the margin of the outer layer of the upper inwardly over the insole where it is secured by the cement.

In the toe-lasting operation the shoe is positioned heightwise by a shoe rest 22 engaging the bottom face of the forepart of the insole substantially as disclosed in Letters Patent No. 2,391,461, granted on December 25, 1945, on an application of mine, except that a spur therein shown for engaging the insole in an indentation formed therein is omitted. The shoe is clamped against this shoe rest substantially at the beginning of a cycle of automatic operations of the machine by upward movement of a toe rest 24 engaging it underneath at the top of the forepart. At substantially the same time a heel rest 26 (Fig. 1) is moved into engagement with the heel end of the shoe to assist in holding it against lengthwise movement, this heel rest as herein shown being constructed as disclosed in the above-mentioned Letters Patent No. 2,391,461.

As shown diagrammatically in Fig. 12 and as disclosed in detail in Letters Patent No. 2,324,509, a pump 28 driven continuously by an electric motor 30 draws operating fluid, preferably light oil, through a pipe 32 from an open reservoir or sump 34 and delivers the fluid through a pipe line 36 to a manifold 38 in which the fluid is maintained under pressure during the cycle of operations, the maximum pressure of the fluid being determined by a spring-controlled relief valve 40 which permits excess fluid to return to the sump. When the machine is not in operation an escape valve 42 permits the fluid to return freely from the manifold to the sump without developing any substantial pressure in the manifold. This valve is closed by a treadle (not shown) to cause the development of such fluid pressure, and simultaneously a valve 44 is operated by the treadle to admit fluid from the manifold through a pipe line 45 to three gripper-closing cylinders shown diagrammatically at 46 in Fig. 12 to cause pistons 48 in these cylinders to close the jaws of the grippers 2 and 4 on the margin of the upper. As fully disclosed in Letters Patent No. 2,324,509, the operator then has the opportunity to see if the upper is properly gripped and if not to cause the grippers to open and to grip it again. After the upper has been properly gripped another depression of the treadle operates a valve 50 to admit fluid from the manifold to a cylinder 52 for rotating a drum 54 having thereon means

for thereafter automatically controlling the valves 42, 44 and 50 and for also controlling other valves associated with various operating instrumentalities of the machine, thus causing the machine to perform a cycle of operations. As distinguished from details of the construction disclosed in Letters Patent No. 2,324,509, such a drum is shown and described in Letters Patent No. 2,337,558.

To assist in understanding the operation of parts hereinafter described, the valve 44 and portions of its controlling mechanism are shown in detail in Fig. 11. The valve is a sleeve valve slidingly mounted on a tubular member 56 which is confined between one wall of the manifold 38 and a coupling member 58 communicating with the pipe line 45 leading to the gripper-closing cylinders 46. The tubular member is in communication at one end with the manifold and at the other end with the coupling member, and it is divided between its opposite ends by a partition 60. Extending through it at one side of the partition are ports 62 and at the other side of the partition ports 64. The valve 44 has therein an annular recess 66 through which communication is afforded between the ports 62 and 64 to admit fluid from the manifold to the gripper-closing cylinders when the valve is in one position, as illustrated in Fig. 11. The valve is controlled by an arm 68 pivotally mounted at 70 on a bracket 72 fast on a plate 74 which serves as the top wall of the manifold 38, the arm carrying a pin 76 extending into an annular groove 78 in the valve. A spring 80 connected to the arm 68 holds the valve initially against one wall of the manifold, at which time communication is interrupted between the ports 62 and 64. The valve being thus in what may be termed its closed position. To move the valve to open position there is provided a lever 82 also pivotally mounted at 70 on the bracket 72 and controlled by the previously mentioned treadle through means including a rod 84. To open the valve the left-hand end of the lever 82, as the parts are viewed in Fig. 11, is swung upwardly by the treadle, and by this movement the lever acts through a compression spring 86 engaging a lug 88 on the arm 68 to swing the arm against the resistance of the spring 80. The opening movement of the valve is adjustably limited by engagement of the arm 68 with a rod 90 threaded at one end in the plate 74 and having on that end a head 92 arranged to be engaged by a wrench for turning it. To maintain the valve in open position there is pivotally mounted at 94 on the lever 82 a latch 96 which, when the lever is operated, enters a notch 98 in a plate 100 fast on the bracket 72 to prevent return of the lever. An arm 102 extending upwardly from the latch 96 is controlled by a spring 104 which causes the latch thus to enter the notch. At the proper time in the operation of the machine the arm 102 is operated by a finger 106 on the drum 54 to withdraw the latch from the notch 98 and thus to cause the valve 44 to be returned to its initial position by the spring 80, whereupon fluid from the gripper-closing cylinders 46 returns to the sump 34 through the ports 64 to cause the grippers to open and release the upper. If the grippers are to grip and pull the upper a second time in accordance with the disclosure of Letters Patent No. 2,337,558, the lever 82 is later operated automatically by the action of an appropriate finger on the drum 54 on its right-hand end with reference to Fig. 11 to move the valve 44 again to open position, after

which another finger on the drum acts at the proper time on the arm 102 to cause the valve to close.

The shoe rest 22 is mounted as heretofore on a slide 108 of skeleton form which is vertically adjustable along guideways on the front frame plate 110 of the machine and is held in place on the guideways by two gibbs 112 (Fig. 5) secured on the rear face of the frame plate. In the construction herein shown the slide 108 is vertically adjusted by means shown in detail in Fig. 3, comprising a spindle 114 having a diametrically enlarged portion 116 confined between two lugs 118 and 120 on the frame plate and threaded in a sleeve 122 secured to the slide. The spindle 114 is provided at its lower end with a knob 124 for turning it. To indicate the position of the slide 108 with respect to adjustment there is pivotally mounted on a stud 126 (Fig. 4) on the frame plate a pointer 128 one end of which is adjacent to a scale 130 on the frame plate and the other end of which has a pin-and-slot connection with a small block 132 fast on the slide.

For purposes of this invention the machine is provided with a pair of arms 134 which are pivotally mounted on studs 136 extending rearwardly from the slide 108 and are connected together by gear teeth 138 so that the arms will swing equal distances toward or from each other. A spring 140 connected to one of the arms and to a member 142 secured to one of the gibbs 112 tends to swing the arms inwardly toward each other, their swinging movements by the spring being adjustably limited by engagement of one of the arms with a screw 144 threaded in the block 132. Accordingly the arms are held initially in the positions determined by the screw. Pivotally mounted on studs 146 on the lower ends of the arms are blocks 148, and connected to each block and to the corresponding arms is a spring 150 which tends to swing the block in one direction about the stud, the movement of the block under the influence of the spring being limited by engagement of a pin 152 on the block with the outer side of the arm. Secured to the blocks 148 are downwardly and inwardly inclined members 154 provided at their lower ends with studs 156 on which are mounted rolls 158 arranged to engage the sides of the shoe. The arms 134 are so positioned initially by the screw 144 that when a shoe is presented to the machine by moving it rearwardly under the shoe rest 22 the rolls 158 and the arms 134 are swung to some extent outwardly away from each other against the resistance of the spring 140 by wedging action of the forepart of the shoe on the rolls, the arms moving equal distances as above described and therefore properly centralizing the forepart of the shoe between the rolls. The operator thus moves the shoe rearwardly to the position determined by engagement of the lower jaw 6 of the end gripper 2 with the upper on the toe-end face of the last, as illustrated in Fig. 9, the end gripper being positioned low enough thus to serve as an end gage by suitable adjustment of the gripper support 5. The gripper support in the construction herein shown is thus adjusted by a small lever 159 (Fig. 1) pivotally mounted on the frame plate 110 and extending rearwardly under the lower end of a member 160 corresponding to the member 98 shown in Letters Patent No. 2,324,509, the lever thus performing the function of the hand wheel 106 shown in said Letters Patent.

Mounted to turn in each of the blocks 148 is a pin 161 having fast on one end thereof a small

block 162 to which is secured a resiliently flexible finger 164 so inclined as to extend downwardly and inwardly to a position over the margin of the upper in a location close to the side gripper 4 between the gripper and the portion of the margin of the upper already secured over the insole, as by pulling-over tacks *t*. The block 162 thus serves as a holder for the finger. Also fast on the pin 161 is a lever 166 having an upwardly extending arm provided with a roll 168 engaged by a piston 170 which is movable in a cylinder 172 formed in the block 148. Movement of the piston 170 by fluid admitted to the cylinder therefore serves to turn the pin 161 and thereby to swing the finger 164 laterally with components of downward and outward movement with respect to the edge of the insole, so that the finger by engagement with the inner face of the more or less upwardly extending portion of the margin of the upper deflects it downwardly and outwardly to position the upper properly between the jaws of the side gripper, as illustrated in Fig. 6. The lever 166 is moved by the piston against the resistance of a return spring 174 (Fig. 7) which is mounted in a bore 176 in the block 148 and presses at one end on a plunger 178 in engagement with a downwardly extending arm of the lever. The spring 174 at its other end abuts against a cylindrical member 180 adjustable by means of a screw 182 threaded in the bore 176, and extending from the member 180 is a stem 184 arranged to engage the plunger 178 to limit positively the movement of the lever 166 and the block 162. Communicating with the outer ends of the two cylinders 172 are flexible tubes 186 leading from a pipe line 188 (Fig. 12) which is tapped into the pipe line 36 leading from the pump 28 to the manifold 38. Accordingly, when the operator first depresses the treadle to move the valve 42 into position to close the outlet from the manifold and the valve 44 into position to admit operating fluid to the gripper-closing cylinders 46, the resulting pressure developed in the manifold and in the pipe line 36 serves to operate the pistons 170 and thus to cause the fingers 164 to position the margin of the upper as above described. To insure that the margin of the upper will thus be properly positioned before it is gripped by the side grippers, movement of the valve 44 (Fig. 11) to admit fluid to the gripper-closing cylinders is so limited by adjustment of the rod 90 that the ports 64 are only partially opened by the valve, as shown in Fig. 11, the closing movements of the grippers being therefore suitably retarded.

To provide necessary clearance for the movements of the upper-trimming means, the toe former 14 and the wipers 20, the arms 134 are swung outwardly about the studs 136 to withdraw the rolls 158 and the fingers 164 from the shoe near the beginning of the cycle of operations of the machine after the shoe has been clamped against the shoe rest 22 by the toe rest 24. For this purpose a vertical cylinder 190 is secured at the rear of the front frame plate 110, the cylinder being provided with a flange 192 confined between the frame plate and one of the gibs 112. Movable in the cylinder is a piston 194 connected by a link 196 to a projection 198 on one of the arms 134. Accordingly, fluid admitted to the lower end of the cylinder operates the piston to swing the arms 134 outwardly, the swinging movements of the arms being limited by engagement of one of them with a pin 200 on the slide 108. Extending from the lower end of the cylinder 190 to the manifold 38 is a pipe line 202 (Fig.

12) through which operating fluid is admitted to the cylinder and is later released therefrom by a valve 204 controlled by means on the drum 54 similarly to other valves with which the machine is provided. As the arms 134 are thus swung outwardly the inclined roll-supporting members 154 are engaged by the edges of plates 206 (Figs. 1 and 8) mounted on the gripper support 5 and are deflected by these plates to positions where they rest on the tops of the plates, as illustrated in Fig. 8, the blocks 148 being swung about the studs 146 against the resistance of the springs 150. Insurance is thus further afforded against any interference with the lasting instrumentalities.

In view of the foregoing description the manner of operation of the machine, in so far as it is of interest with reference to the present invention, need be only briefly summarized. Before presenting a shoe to the machine the operator turns the margin of the toe end of the upper outwardly, especially about the end of the toe where this may be readily done, the toe end of the upper having been softened in a toe steamer as usual prior to lasting. In presenting the shoe the operator positions the bottom of the toe end of the insole against the shoe rest 22 and moves the shoe lengthwise in a rearward direction between the rolls 158, the rolls and their supporting arms 134 being forced apart equal distances by the wedging action of the shoe on the rolls. The rearward movement of the shoe is limited by engagement of the upper on the toe-end face of the last with the lower jaw 6 of the end gripper 2, as illustrated in Fig. 9, the rolls then engaging the shoe in locations beyond its toe portion. By the outward movements of the arms 134 the fingers 164 are properly positioned widthwise of the shoe relatively to the portions of the margin of the upper located between the side grippers 4 and the side pulling-over tacks *t*, as illustrated in Fig. 5. After having thus presented the shoe, the operator, by depression of the previously mentioned treadle, moves the valve 42 into position to close the outlet from the manifold 38 and thus to cause the development of fluid pressure in the manifold and moves the valve 44 into position to admit the fluid to the gripper-closing cylinders 46. In response to the development of such fluid pressure the pistons 170 are immediately operated to impart downward and outward swinging movements to the fingers 164, causing the fingers to depress and to spread the portions of the margin of the upper which they engage and thus to position the upper properly between the jaws of the side grippers 4 as shown in Fig. 6. In this operation the fingers may be flexed to some extent in response to resistance of the upper, the movements of the finger-operating levers 166 being limited by engagement of the pins 184 with the plungers 178 engaged by the lower ends of the levers. Simultaneously with the movements of the fingers the grippers begin to close on the upper, but in view of the manner in which the valve 44 is controlled, as hereinbefore described, the closing of the jaws is retarded to insure that the margin of the upper will be properly positioned by the fingers before it is gripped. Thereafter, by another depression of the treadle, the operator moves the valve 50 to start the cycle of operations. Substantially at the beginning of the cycle the toe rest 24 is moved upwardly to clamp the shoe against the shoe rest 22 and the heel rest 26 is moved into operative position. Near the beginning of the cycle also, after the clamping of the shoe, fluid is admitted by the

valve 204 to the cylinder 190 to cause the rolls 158 and the fingers 164 to be withdrawn from the shoe by the arms 134, the roll-supporting members 154 being deflected upwardly by the plates 206 to positions on the tops of the plates, as illustrated in Fig. 8. Thereafter the machine continues and completes its cycle, operating on the shoe in a manner which need not be further described in view of the disclosures in the previously mentioned Letters Patent. Substantially at the end of the cycle the valve 204 releases the fluid from the cylinder 190 and the arms 134 are returned by the spring 140 to the positions determined by the screw 144, the members 154 being swung downwardly by the springs 150. When the pressure in the manifold is terminated by the valve 42 at the end of the cycle the springs 174 impart upward return movements to the fingers 164.

It is to be understood that with respect to the means for positioning the shoe the invention, in some aspects, is not limited to an organization including means for positioning the margin of the upper relatively to gripper jaws as shown and described, and that such upper-positioning means, moreover, may be useful in association with a gripper or grippers arranged to act on an upper elsewhere than at its toe-end portion.

Having described the invention, what I claim as new and desire to secure by Letters Patent of the United States is:

1. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, and means for properly positioning the upper between the jaws of said grippers before it is thus gripped by engagement with portions of its margin located between said grippers and the portions of the upper extending inwardly over the insole.

2. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, and members arranged to engage portions of the margin of the upper located between said grippers and the portions of the upper extending inwardly over the insole and movable properly to position the upper between the jaws of said grippers before it is gripped.

3. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable generally heightwise of the last to grip the margin of the upper between them in outspread relation to the edge of the last bottom, and means movable to spread the upper outwardly between the jaws of said grippers before it is thus gripped by engagement with portions of its margin located between said grippers and the portions of the upper extending inwardly over the insole.

4. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable generally heightwise of the last to grip the margin of the upper between them in outspread relation to the edge of the last bottom, and members having components of movement heightwise and widthwise of the last properly to position the upper between the jaws of said grippers before it is thus gripped by engagement with portions of its margin located between said grippers and the portions of the upper extending inwardly over the insole.

5. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the margin of the upper between them in outspread relation to the edge of the last bottom, and fingers inclined heightwise and widthwise of the last and movable laterally about axes extending lengthwise of the last to spread the upper outwardly between the jaws of said grippers before it is thus gripped by engagement with portions of its margin located between said grippers and the portions of the upper extending inwardly over the insole.

6. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the margin of the upper between them in outspread relation to the edge of the last bottom, fingers movable laterally to spread the upper outwardly between the jaws of said grippers before it is thus gripped by engagement with portions of its margin located between said grippers and the portions of the upper extending inwardly over the insole, and holders for said fingers movable about axes extending lengthwise of the last to operate them, the fingers being resiliently flexible to permit them to yield in response to resistance of the upper.

7. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the margin of the upper between them in outspread relation to the edge of the last bottom, fingers movable laterally to spread the upper outwardly between the jaws of said grippers before it is thus gripped by engagement with portions of its margin located between said grippers and the portions of the upper extending inwardly over the insole, said fingers being resiliently flexible to permit them to yield in response to resistance of the upper, holders for said fingers mov-

11

able to operate them, and means for positively limiting the movements of said holders.

8. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, and fluid-pressure means for simultaneously operating said members and closing the jaws of said grippers but for retarding the closing of said jaws to permit the upper to be properly positioned before it is gripped.

9. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, and means for positioning said members relatively to the shoe widthwise thereof as determined by engagement with the opposite sides of the shoe.

10. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, and supports for said members relatively to which they are thus movable, said supports being movable relatively to each other widthwise of the shoe and having means thereon for engaging the sides of the shoe to position said members widthwise of the shoe as determined by such engagement.

11. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, and arms supporting said members and relatively to which they are thus movable, said arms being mounted for swinging movements away from each other and being thus yield-

12

ingly movable by wedging action of the shoe thereon to position said members relatively to the shoe widthwise thereof.

12. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, supports for said members relatively to which they are thus movable, said supports being movable relatively to each other widthwise of the shoe and having means thereon for engaging the sides of the shoe to position said members widthwise of the shoe as determined by such engagement, and cylinder-and-piston devices on said supports for operating said members by fluid pressure.

13. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, supports for said members relatively to which they are thus movable, and means for moving said supports to withdraw said members from the shoe after the upper has been gripped by the grippers.

14. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, and supports for said members mounted for movements in directions widthwise of the shoe and having thereon means for positioning the shoe laterally by engagement with its opposite sides.

15. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, and supports for said

members having means thereon for positioning the shoe laterally by engagement with its opposite sides, said supports being connected together for equal movements toward and from each other and being yieldingly movable away from each other by wedging the action of the shot thereon when the shoe is presented to the machine.

16. In a lasting machine, grippers for gripping the margin of an upper mounted on a last and for pulling the upper at the opposite sides of the toe respectively in locations near portions of the upper extending inwardly over an insole on the last at the sides of the forepart beyond the toe, said grippers each comprising a pair of upper-gripping jaws relatively movable to grip the upper between them, members movable properly to position the upper between the jaws of said grippers before it is thus gripped by engagement with portions of its margin located between said grippers and the portions of the upper extending inwardly over the insole, supports for said members having means thereon for positioning the shoe laterally by engagement with its opposite sides, means for clamping the shoe to hold it in the position thus determined, and means for moving said supports to withdraw said members and shoe-positioning means from the shoe after the shoe has thus been clamped.

17. In a lasting machine, a gripper for gripping the margin of an upper mounted on a last and for pulling the upper in a location near a portion thereof previously secured to the bottom face of an insole on the last, said gripper comprising a pair of upper-gripping jaws relatively movable to grip the upper between them, and a device arranged to engage the margin of the upper in a location between said gripper and the portion of the upper secured to the insole and movable to position the upper properly between the jaws of the gripper before it is thus gripped.

18. In a lasting machine, a gripper for gripping the margin of an upper mounted on a last and for pulling the upper in a location near a portion thereof previously secured to the bottom face of an insole on the last, said gripper comprising a pair of upper-gripping jaws relatively movable to grip the upper between them in outspread relation to the edge of the last bottom, and a device arranged to engage the margin of the upper in a location between said gripper and the portion of the upper secured to the insole and movable to spread the margin of the upper outwardly between the jaws of the gripper before it is thus gripped.

19. In a lasting machine, a gripper for gripping the margin of an upper mounted on a last and for pulling the upper in a location near a portion thereof previously secured to the bottom face of an insole on the last, said gripper comprising a pair of upper-gripping jaws relatively movable to grip the upper between them, and a member arranged to press on the inner face of the margin of the upper in a location between said gripper and the portion of the upper secured to the insole and movable in the direction of the pressure thus applied to said face to position the upper properly between the jaws of the gripper before it is thus gripped.

20. In a lasting machine, a gripper for gripping the margin of an upper mounted on a last and for pulling the upper in a location near a portion thereof previously secured to the bottom face of an insole on the last, said gripper comprising a pair of upper-gripping jaws relatively

movable to grip the upper between them in outspread relation to the edge of the last bottom, and a member arranged to press on the inner face of the margin of the upper in a location between said gripper and the portion of the upper secured to the insole and having components of movement heightwise of the last and outwardly with respect to the edge of the last bottom in the direction of the pressure thus applied to said face to deflect the margin of the upper into proper position between the jaws of said gripper before it is thus gripped.

21. In a lasting machine, a gripper for gripping the margin of an upper mounted on a last and for pulling the upper in a location near a portion thereof previously secured to the bottom face of an insole on the last, said gripper comprising a pair of upper-gripping jaws relatively movable to grip the upper between them, a finger arranged to extend lengthwise in oblique angular relation to the bottom of the shoe and to engage the inner face of the margin of the upper in a location between said gripper and the portion of the upper secured to the insole, and means for swinging said finger laterally in a direction transversely of the edge of the shoe bottom to deflect the margin of the upper into proper position between the jaws of said gripper before it is thus gripped.

22. In a lasting machine, a gripper for gripping the margin of an upper mounted on a last and for pulling the upper, said gripper comprising a pair of upper-gripping jaws relatively movable to grip the margin of the upper between them in outspread relation to the edge of the last bottom, and a member arranged to press on the inner face of the margin of the upper and movable in the direction of the pressure thus applied to said face to spread the margin of the upper outwardly between the jaws of said gripper before it is thus gripped.

23. In a lasting machine, a gripper for gripping the margin of an upper mounted on a last and for pulling the upper, said gripper comprising a pair of upper-gripping jaws relatively movable to grip the margin of the upper between them in outspread relation to the edge of the shoe bottom, a finger arranged to extend lengthwise in oblique angular relation to the bottom of the shoe and to press on the inner face of the margin of the upper, and means for swinging said finger laterally with components of movement heightwise of the shoe and outwardly with respect to the edge of the shoe bottom to deflect the margin of the upper into proper position between the jaws of said gripper before it is thus gripped.

24. In a lasting machine, a gripper for gripping the marginal portion of an upper on a last at the end of the toe and for pulling the upper, said gripper being arranged to position the shoe lengthwise by engagement with the upper on the toe-end face of the last when the shoe is presented to the machine, and means for further positioning the shoe laterally by engagement with the upper on the opposite side faces of the forepart of the last.

25. In a lasting machine, a gripper for gripping the marginal portion of an upper on a last at the end of the toe and for pulling the upper, said gripper comprising a pair of jaws relatively movable generally heightwise of the last to grip the upper and being arranged to position the shoe lengthwise by engagement of one of said jaws with the upper on the toe-end face of the last.

15

when the shoe is presented to the machine, and means for further positioning the shoe laterally by engagement with the upper on the opposite side faces of the forepart of the last.

26. In a lasting machine, a gripper for gripping the marginal portion of an upper on a last at the end of the toe and for pulling the upper, said gripper being arranged to position the shoe lengthwise by engagement with the upper on the toe-end face of the last when the shoe is presented to the machine, and members for further positioning the shoe laterally by engagement with the upper on the opposite side faces of the forepart of the last, said members being connected together for equal movements toward and from each other and being so positioned initially as to be forced apart by wedging action of the shoe thereon when the shoe is presented.

27. In a lasting machine, a gripper for gripping the marginal portion of an upper on a last at the end of the toe and for pulling the upper, said gripper being arranged to position the shoe lengthwise by engagement with the upper on the toe-end face of the last when the shoe is presented to the machine, members for further positioning the shoe laterally by engagement with the upper on the opposite side faces of the forepart of the last, means for clamping the shoe to hold it in the position determined by said gripper and members, and means for moving said members away from the shoe after it has thus been clamped.

28. In a lasting machine, a gripper for gripping the marginal portion of an upper on a last at the end of the toe and for pulling the upper, said gripper being arranged to position the shoe lengthwise by engagement with the upper on the toe-end face of the last when the shoe is presented to the machine, members for further positioning the shoe laterally by engagement with the upper on the opposite side faces of the forepart of the last, said members being connected together for equal movements toward and from each other and being so positioned initially as to be forced apart by wedging action of the shoe thereon when the shoe is presented, means for clamping the shoe to hold it in the position determined by said gripper and members, and means for moving said members farther apart to withdraw them from the shoe after it has thus been clamped.

29. In a lasting machine, members arranged to

16

engage the opposite sides of the forepart of a shoe to position the shoe laterally and to be forced apart by wedging action of the shoe thereon when it is presented to the machine, means for clamping the shoe to hold it after it has thus been positioned, and means for moving said members farther apart to withdraw them from the shoe after it has thus been clamped.

30. In a lasting machine, members arranged to engage the opposite sides of the forepart of a shoe to position the shoe laterally, supports for said members mounted for swinging movements away from each other laterally of the shoe each about an axis extending lengthwise of the shoe by wedging action of the shoe on the members when it is presented to the machine, means for clamping the shoe to hold it after it has thus been positioned, and means for swinging said supports farther apart to withdraw the members from the shoe after it has thus been clamped.

31. In a lasting machine, members arranged to engage the opposite sides of the forepart of a shoe to position the shoe laterally, means for clamping the shoe to hold it after it has thus been positioned, and means for moving said members widthwise of the shoe to withdraw them from the shoe after it has thus been clamped and for also moving them heightwise of the shoe in the course of their movements widthwise of the shoe.

32. In a lasting machine, members arranged to engage the opposite sides of the forepart of a shoe to position the shoe laterally, means for clamping the shoe to hold it after it has thus been positioned, means for moving said members widthwise of the shoe to withdraw them from the shoe after it has thus been clamped, and additional means for moving said members heightwise of the shoe in response to their movements widthwise of the shoe.

33. In a lasting machine, members arranged to engage the opposite sides of the forepart of a shoe to position the shoe laterally, means for clamping the shoe to hold it after it has thus been positioned, arms supporting said members and movable widthwise of the shoe to withdraw them from the shoe after it has thus been clamped, and means for also moving said members heightwise of the shoe relatively to the arms in response to the movements of the arms.
